UNITED STATES PATENT OFFICE.

ADOLPH S. LARSON, OF NORTH LAKE, WISCONSIN.

LIFTING JACK.

Application filed January 24, 1925. Serial No. 4,499.

The invention relates to lifting jacks.

The object of the invention is to provide a lifting jack having a relatively low height so that it may be used in places where the distance between the member to be lifted and the jack's support is relatively low, and to this end the jack has a collapsible standard composed of a plurality of articulated members that are so arranged as to be moved from a position in one plane to a position in the lifting plane.

A further object of the invention is to provide a jack in which the collapsible lifting standard is composed of a plurality of members, some of which may be removably connected so that the effective height of the lifting standard may be varied.

The invention further consists in the several features hereinafter set forth and more particularly defined by claims at the conclusion hereof.

In the drawings: Fig. 1 is a side elevation view of a lifting jack embodying the invention;

Fig. 2 is a vertical sectional view through the device taken on the line 2—2 of Fig. 3; Fig. 3 is a plan view of the device.

In the drawings the numeral 4 designates the frame of the device, having a base portion 5 and side portions 6 forming a longitudinally extending guide channel 7.

The collapsible lifting standard is formed by a plurality of articulated members 8. With the exception of the top members, each of these members is in the form of a link having a block portion 9, a pintle portion 10, a hook portion 11 and a sprocket recess 12.

A part of each block adjacent its pintle is recessed, as at 13, so that the hook portion 11 may be slipped past this recess and over the pintle to assemble the links, though some of the links may not have this detachable connection. The detachable connection, however, enables as many links to be assembled as desired, and this, it will be seen, permits of the use of lifting standards of varying heights to suit operating conditions. The members 8 are assembled to form what may be termed two sections which are hingedly connected at one of their ends, through the top members, by a hinge 14, and which are adapted to abut against each other to form the lifting standard.

To move the parts of the articulated standard to an operating position and maintain them in such position, each articulated

section is adapted to engage a sprocket 15 and is guided to an upright or abutting position by the side portions 6 and a bottom guide 16 which merges into a curved guide 17 adjacent the sprockets, the curved guides meeting each other at a center line between the center lines of the axis of the sprockets 15. Each of the sprockets 15 is removably mounted on a shaft 18 journaled in the sides of the frame and carrying a worm wheel 19. Each worm wheel 19 meshes with a worm 20 formed integral with or secured to a shaft 21 which may be turned in any suitable manner, as by a hand-crank 22 connected to said shaft 21.

With this construction, when the parts are shown in their lowered position, as in Fig. 2, the turning of the shaft 21 in the proper direction will, through the gears 20 and 19, rotate the shafts 18 and their sprockets 15 which, meshing with the chain-type sections, moves the parts of the standard upwardly into a lifting position, as shown in Fig. 1, and the turning of said shaft in the opposite direction will serve to return the parts of the collapsible standard to the position shown in Fig. 2.

Inasmuch as the parts of the standard move from a horizontal to a vertical position, it will be appreciated that the overall height of the jack is relatively small so that it may be used in places where the ordinary jack cannot be used.

The tops of the top members 8 of the standard may be inclined slightly, as shown at 23, and a cap member 24 may be fitted over them and detachably secured in position by a removable pin 25.

Because of the gearing connections used when the shaft 21 is not being rotated, the sprockets 15 will be prevented from rotating and the standard will thus be held in an adjusted position.

It will be noted that the pivot connections of the links of each section face outwardly and that the sides of adjacent links of one section abut against each other, and that the links of adjacent sections abut against each other when in operative position to form the lifting standard.

I desire it to be understood that this invention is not to be limited to any particular form or arrangement of parts except in so far as such limitations are included in the claims.

What I claim as my invention is:

1. In a lifting jack, the combination with a frame, of a pair of articulated chain type sections operatively connected together and movable toward and away from each other to form a collapsible lifting standard, guide means for turning the sections from horizontal to vertical, sprockets engageable with the links of each of said sections at the turn to operate the standard, the guide means extending upwardly to substantially the center line between the axes of said sprockets, and means for actuating said sprockets.
2. In a lifting jack, the combination with a frame having open troughs, of a pair of articulated lifting sections operatively connected together and movable toward and away from each other in said troughs to form a collapsible lifting standard, each of said sections comprising a series of articulated blocks with a single sprocket tooth engaging recess in each block, guide means for turning the sections from horizontal to vertical, sprockets engageable with the links of said sections at the turn to operate the standard, and means for actuating said sprockets.

In testimony whereof, I affix my signature.

ADOLPH S. LARSON.
